UNITED STATES PATENT OFFICE.

SHELDON CARY, OF BROOKLYN, NEW YORK.

IMPROVEMENT IN SUSPENSION-RINGS.

Specification forming part of Letters Patent No. 123,553, dated February 13, 1872.

SPECIFICATION.

I, SHELDON CARY, of Brooklyn, State of New York, have invented certain Improvements in Suspension-Rings, of which the following is a specification:

The object of my invention is to produce suspension-rings for the purpose of attaching the same to cards, papers, labels, or samples, by which the same can be hung up or fastened to other goods in a more convenient, more secure, and cheaper manner than heretofore.

Figure I is a front view of my invention. Fig. II is a side view of the same.

In order to enable those skilled in the art to produce my improved suspension-rings, I shall proceed to describe the mode in which they are manufactured.

I cut from a light brass wire a number of pieces of the same length. By the use of a pair of pliers I make a true circle, A, in the middle of the wire, and straighten out the ends of the wire B B parallel to each other. By the plier I form on the end of one of the wire ends a circular eye, C; on the end of the other a short bend, D, under a right angle. Thus my improved suspension-rings are easily and rapidly manufactured by the aid only of a pair of pli-

ers in any skilled workman's hands. Of course, suitable machinery may be employed for the same purpose.

For the purpose of attaching my improved suspension-rings anywhere desired I merely thrust the short bend D into the card, label, or sample, if the fabric will allow it; if not, I perforate the same with a knife, needle, or any tool convenient at hand. I then insert the short bend D into the eye C and press the end of the bend down parallel to the wire B. Thus my improved suspension-ring is securely fastened and locked.

Having thus fully described and specified my invention, I desire to claim—

As an article of manufacture, the within-described suspension-ring, made of a single piece of wire, with circle A, two parallel bars, B B, bent to extend downward exactly in front of one another, the extremity of one bar forming an eye, C, while the extremity of the other is bent at right angles inward and forms a hook, which passes through the eye, and there secured, all as shown and set forth.

Witnesses: SHELDON CARY.
